SUCTION ROLL AND METHOD OF DRILLING
SAMEAlbert H. Standley, Downingtown, Pa., assignor
to Downingtown Manufacturing Company,
Downingtown, Pa., a corporation of Pennsyl-
vania

Application April 3, 1934, Serial No. 718,880

3 Claims. (Cl. 92—53)

This invention relates to suction rolls, and more particularly to a method of drilling the same to prevent water-throwing by the roll in operation. As is well known to those familiar with the art, a suction roll comprises a perforated shell rotating about a stationary suction box, the suction of which operates through the openings of the shell to withdraw water from a web-supporting carrier traveling over the shell. Since the suction effort is exerted throughout the box area, water is drawn into the openings of the shell until the time when the shell passes over the final packing strip of the suction box, consequently, a certain amount of water is left in the openings which is not drawn into the suction box and this water tends to throw from the openings under the influence of centrifugal force. The flying water, particularly with a rapidly rotating suction roll, is often objectionable to the mill operator, particularly where this water, in leaving the roll, is thrown against the carrier on which the roll operates for the purpose of drying the same.

An important object of this invention is the provision of a suction roll construction in which the openings are so arranged that they tend to overcome the action of centrifugal force and thus prevent water forming and further tend to act as buckets taking in air from the outer ends as the roll is rotated so that the air further acts to prevent outward movement of water in the openings instead of acting to assist the same as in the usual construction.

These objects I attain by arranging the openings of the shell as illustrated in the accompanying drawing in which

The figure shows an enlarged section of a suction roll shell with a contacting felt and a fragment of an associated press roll.

In accordance with my method, the openings 10 of the shell 11 are given a circumferential rake, having their outer ends in advance of their inner ends as regards the direction of rotation of the shell indicated by the arrow in the drawing, the axis of these openings being preferably similarly tangential to a theoretical cylinder 12 of predetermined diameter coaxial with shell 11.

It will be obvious that with this arrangement, centrifugal force, which operates radially, will tend to force the water against the rear wall of

the opening rather than directly from the opening as in the ordinary construction, and that the friction thus set up resisting the outward movement of the water will be assisted during the upper cycle of rotation of the roll by gravity so that during engagement of the roll with the carrier 13, bearing the web 14 acted on by the roll, there will be much less tendency of water to be thrown from the openings and against the carrier 13. Furthermore, the rotation of the shell 10 produces an air current which, passing over the radially-directed openings of an ordinary shell, acts with an aspirating effect assisting the movement of the water outwardly in the openings while with the openings canted forwardly in the direction of rotation, as in the present structure, this current instead of producing an aspirating effect produces a pressure effect in the opening which further assists in preventing outward movement of the water. Additionally, as the openings more nearly approach the carrier, air trapped between the carrier and the periphery of the roll will be forced through these openings increasing the inward pressure exerted on water in the openings. The openings 10 may be given any suitable rake angle although this angle should not be increased to an extent leading to difficulties in formation of the openings as a result of the sharp angle between the drill and the surface of the shell 11.

I claim:

1. A suction roll shell adapted for rotation in a given direction and having suction openings formed therein, those portions of said suction openings which extend through the periphery of the shell being axially inclined radially forwardly in the direction of rotation.

2. A suction roll shell adapted for rotation in a given direction and having suction openings formed therein, those portions of said suction openings which extend through the periphery of the shell being axially inclined radially forwardly in the direction of rotation, said openings being tangential to a cylinder coaxial with the shell.

3. A suction roll shell having drilled suction openings, the outer ends of the suction openings being in advance as regards the direction of rotation of the shell.

ALBERT H. STANLEY.
